CHANCE CONTROLLED FOOTBALL GAME
BOARD

Arthur C. Stringer, Jackson, Miss.

Application June 2, 1948, Serial No. 30,643

1 Claim. (Cl. 273—94)

1

This invention relates to games wherein opposing teams or players use offensive and defensive maneuvers and wherein a number of types of plays are available to the offense. Under such circumstances the ability of the defense to anticipate which type of play available to the offense will be used enables the former to more effectively block or nullify the play.

An object of the invention is to embody realistically in a game of this kind means whereby actual knowledge of the game and how it should be played may be used to advantage by each player.

Another object of the invention is to eliminate, so far as possible, the factor of chance in directing progress of a game, enabling an alert defense to profit at the expense of the offense, and vice versa.

More specifically it is an object of the invention to embody in a game of the character described means whereby the offense may select for use a type of play from various plays known by each player or team to be available and means for indicating the result of any selected type of play from both successful defensive and successful offensive viewpoints, together with an arrangement whereby the success or lack thereof of a defensive player in anticipating in advance the type of play selected by the offensive player determines the results of the play.

The invention is well suited to games simulating various types of sports such as hockey, football, baseball, etc., and for purposes of illustration I have selected the game of football.

Various other objects and meritorious features of the invention will be apparent from the following description taken in conjunction with the drawings, wherein like numerals refer to like parts throughout the several figures, and wherein:

Fig. 1 is a top plan view of a gameboard suited to my invention, and

Figs. 2 and 3 represent equipment used in conjunction with the board by offense and defense.

The playing board is broadly designated by the numeral 10 and represents the gridiron of a football field. The yardage is indicated in the customary manner by transverse lines 12 extending across the board at five-yard intervals, the yardage indicated by each line being designated by numerals 14 located at each end of each five-yard marker line. The numerals 14 are located along opposite margins of the board and extend from zero at each end to the midfield fifty-yard point.

Extending longitudinally near one margin of the board is a groove or trackway 16 in which the simulation of a football 18 is slidably mounted. The simulation of the ball is preferably provided with a needle point 20 adapted to align with the

2

one-yard indicating lines 22 to facilitate accurate positioning of the ball in accordance with the called play.

Extending parallel to groove 16 and relatively closely adjacent thereto is a second groove or trackway 24 in which a ten-yard marker 26 is mounted for sliding movement. Each end of the ten-yard marker is provided with needle points 28 for alignment with the single-yard markings 22 to facilitate accurate positioning of the marker for determining the point on the board or field which the ball must reach in four downs in order to entitle the offense to a first down and consequently another play.

15 Printed on the board in such manner as not to interfere with the general gridiron effect thereof is a list 30 of plays available to the offense. This list may be printed in more than one location, preferably in oppositely disposed relationship as shown on the drawings, to facilitate its use by players located on opposite sides of the board.

20 At some other position on the board selected to interfere least with the gridiron effect is a pivoted pointer or indicator 32 which is adapted to swing about a dial indicating the downs used by the offense. There is also a pointer or indicator 34 pivoted at some other inconspicuous point on the board and adapted to be swung about a printed dial face 36 indicating the number of plays.

25 For purposes of illustration, dial 36 is provided with sections denoting plays up to twenty-five and each succeeding group of five may be colored differently from its adjacent group of five to aid in quick determination of the extent to which the game has progressed. Twenty-five plays make a quarter and of course four quarters complete the game.

30 Conspicuously located on the board for quick and ready reference is a large circular dial broadly indicated by the numeral 38. Delineated by suitable marking on this dial are a plurality of concentric annuli. For purposes of illustration I have shown three concentric inner annuli designated by the letters a, b and c surrounding which are five outer annuli divided, respectively, into subannuli d—d', e—e', f—f', g—g', and h—h'. It will be noted that to aid in readily distinguishing the different annuli and subannuli, the main annuli are separated by double lines and the subannuli, are separated by single lines. Other means of designating these differences such as differently colored lines would be equally satisfactory.

35 Passing through the dial, or at least the annuli thereof, are radial lines indicated generally at 42 dividing the dial into segments. Each pair of adjacent subannuli within each segment bears legends appropriate to offensive and defensive play, respectively. Thus, in the segment designated 44

subannuli *h*' contains the legend "Gain 4," an advantage for the offense, whereas subannuli *h* bears the legend "Lose 1," obviously a loss to the offense and a relative gain for the defense.

An indicator 46 is rotatably mounted at the center of the dial, which indicator on one side of its axis is divided transversely into sections designated 1, 2, 3, 4, 5, 6, 7, 8, and each section overlies one of the main annuli of the dial.

It will be noted that the list 30 of plays designated in this illustrative embodiment of the invention are eight in number and are so numbered. The first five listed plays are those which may be made from scrimmage or from a so-called "huddle." Plays 6, 7 and 8 are plays of a different type. The numbers of the sections on indicator 46 correspond to the numbers of the plays in list 30. Annuli *a*, *b* and *c* are not divided into subannuli because these annuli relate to plays 6, 7 and 8 which, as will be seen from list 30, constitute a "punt runback," a "field goal," and an "extra point." For the two kicking plays 7 and 8 the play can be only good or bad, as indicated on the dial, and for a runback of a punt the yardage of the run only need be indicated, as will be noted in annuli 6.

For all other plays, to wit, plays from 1 to 5 in list 30, the defense, by anticipating the play which the offense proposes to make, may well turn the play to its advantage. To impart realism into the play of the game and enable the players to utilize their own knowledge and skill in the finer points of tactics and play, a series of five chips labeled as indicated in Fig. 2 are provided for the offensive player and a similar series of chips illustrated in Fig. 3 are provided for the defensive player. It will be noted that these chips correspond to the plays designated 1 to 5 in list 30 on the face of the board. Preferably the chips for each of the two opposing players are of different colors to facilitate ready distinction.

When in a position to make any of the plays designated 1 to 5 in list 30, the offense lays the chip representing the selected play face up on the board but covered. The defense, after determining which is the most likely play for the offense under the particular conditions extant on the field, selects the chip designating that play and lays it in similar manner on the board. If the chip of the defense matches the chip of the offense when both chips are uncovered, it is evident that the defense has succeeded in anticipating the play about to be made by the offense.

The indicator 46 is then spun. Assuming that play 3 has been selected, a forward pass, and the indicator 46 comes to rest at the position indicated in Fig. 1, the legend in that segment of the dial within subannuli *f* will determine the result of the play. If the defense had not succeeded in anticipating the play and had failed to match the chip selected by the offense, the legend appearing in the segment over which the indicator rests and within subannuli *f*' would determine the result of the play. Thus, if the defense failed successfully to anticipate the forward pass, the result of the play would be an incomplete pass. If the defense had successfully anticipated the play to be made by the offense, the result of the play would be a pass of twenty yards by the offense intercepted by the defense, thus giving the defense the ball and starting it on its march toward the goal of its adversary. Thus the legends in subannuli *d*', *e*', *f*', *g*' and *h*' designate the result of a play which was not successfully anticipated by the defense while those in suban-

nuli, *d*, *e*, *f*, *g* and *h* designate the result of the corresponding same plays where the defense successfully anticipated the play in advance of its execution by spinning the indicator 46.

It is obvious that more than the eight plays illustrated may be designated, and that the plays may be of any type suitable for any particular game. It is likewise apparent that the legends indicating the results of the play for both successful offense and successful defense may be varied to suit different types of games and different styles of playing the same.

While I have described the game in conjunction with football, it will be apparent that the basic invention is applicable to games of various sorts wherein different plays are available to the offense and the defense gains advantage by successfully anticipating which of these plays the offense will make. Games relating to other than sports may well be arranged in accordance with the invention. Games relating to war maneuvers, etc., may readily be adapted to the basic principles herein described. For these and various other reasons, modifications of the particular illustrative embodiment herein disclosed may be apparent to those skilled in the art and I wish therefore to be limited only within the scope of the appended claim.

What I claim is:

30 A football game comprising a board bearing a circular dial having delineated thereon a plurality of concentric annuli, certain of said annuli being divided into subannuli, the annuli being delineated by double circles and the subannuli by single circles, radial lines passing through said annuli and dividing the dial into segments, each annuli within each segment bearing a legend appropriate to offensive play only, each pair of adjacent subannuli within each segment bearing 35 legends appropriate to offensive and defensive play, respectively, an elongated indicator rotatably mounted at the center of the dial, said indicator on one end of its axis being divided transversely into sections overlying, respectively, each 40 annuli and each pair of adjacent subannuli and bearing, respectively, marks identifying a type of play, means bearing marks corresponding to those on said indicator enabling the offense to select unknown to the defense a type of play to be attempted, and separate means bearing marks corresponding to those on said indicator enabling the defense to attempt successfully to anticipate in advance of play what type of play is selected, 45 whereby, when the indicator is spun, in accordance with the defense's success or lack thereof, the defensive or offensive legend on that portion 50 of the subannuli over which the selected play- identifying portion of the indicator stops directs the movement of the ball.
